[57] CLAIM

The ornamental design for a pipe support for a watering system, as shown and described.

DESCRIPTION

FIG. 1 is a perspective view of a pipe support for a watering system with the broken line showing of a ballast pipe, a conduit and a dispenser valve being for

illustrative purposes only and forming no part of the claimed design;

FIG. 2 is a left side view thereof;

FIG. 3 is a right side view thereof;

FIG. 4 is a rear view thereof;

FIG. 6 is a top plan view thereof;

FIG. 7 is a bottom plan view thereof;

FIG. 8 is a perspective view of the bottom portion thereof;

FIG. 9 is a left side view of the bottom portion thereof;

FIG. 10 is a right side view of the bottom portion thereof;

FIG. 11 is a front view of the bottom portion thereof;

FIG. 12 is a rear view of the bottom portion thereof;

FIG. 13 is a top plan view of the bottom portion thereof;

FIG. 14 is a bottom plan view of the bottom portion thereof;

FIG. 15 is a perspective view of the middle portion thereof;

FIG. 16 is a left side view of the middle portion thereof;

FIG. 17 is a right side view of the middle portion thereof;

FIG. 18 is a rear view of the middle portion thereof;

FIG. 19 is a front view of the middle portion thereof;

FIG. 20 is a top plan view of the middle portion thereof;

FIG. 21 is a bottom plan view of the middle portion thereof;

FIG. 22 is a perspective view of the top portion thereof;

FIG. 23 is a side view of the top portion thereof;

FIG. 24 is a front view of the top portion of the connector with the view of the opposite side being a mirror image;

FIG. 25 is a top plan view of the top portion thereof;

FIG. 26 is a bottom plan view of the top portion thereof; and,

FIG. 27 is an exploded perspective view.

The views in FIGS. 8-27 show portions of the claimed design in separated condition for clarity of illustration only.
